PNEUMATIC COUPLER FOR MUSICAL INSTRUMENTS

Filed Jan. 24, 1927

Inventor:
Lewis T. Barkstrom,
By J. Clark Stacey, atty

1. A pneumatic coupler for musical instruments, comprising a horizontally extending duct-bar, a series of tubular conduits extending from the lower part of the duct-bar, a series of tubular conduits extending from the upper part of the duct-bar, a key-operable valve-action, a tracker-controllable valve-action, a series of individual ducts in the key-operable valve-action, a series of individual ducts in the tracker-controllable valve-action, and a plurality of valve-connections connecting the tubular conduits with the individual ducts.

UNITED STATES PATENT OFFICE

LEWIS T. BARKSTROM, OF CHICAGO, ILLINOIS, ASSIGNOR TO J. P. SEEBURG PIANO COMPANY, OF CHICAGO, ILLINOIS, A CORPORATION OF ILLINOIS

PNEUMATIC COUPLER FOR MUSICAL INSTRUMENTS

Application filed January 24, 1927. Serial No. 163,111.

This invention relates to couplers for musical instruments, and more particularly concerns pneumatic couplers for key-controlled, automatically controlled, and combined key and automatically controlled instruments.

The principal object of the invention is to provide a coupler of the aforesaid character which is simple in construction and efficient in operation, not likely to get out of order, not liable to leakage, and which may be constructed in the preferred form herein shown as a compact and separately removable unit.

Further objects, features and advantages of the invention will more fully appear in the detailed description to follow.

In the drawings:

Figure 1 is a fragmentary, perspective view of a pneumatic coupler constructed according to this invention, two similar transverse sections being taken through different parts of the structure to illustrate the relationship and interconnection of the several series of coupler-ducts;

Fig. 1^a is a detail, showing in perspective one of the coupler-valves of Fig. 1, part of the valve being broken away to expose the underlying structure;

Fig. 2 is a sectional view of a conventional form of coupler draw-stop which may be used in connection with the pneumatic coupler shown in Fig. 1 to control the operativeness thereof;

Fig. 3 is a sectional view, somewhat diagrammatic in character, of a conventional form of automatic controlling means, such as is employed to control the operation of automatically controlled musical instruments, comprising the well known music sheet, tracker, and tracker-controllable valve-action, with which the pneumatic coupler of Fig. 1 is designated to co-operate; and

Fig. 4 is a sectional view of a conventional form of manual key-board and key-operable valve-action, such as is employed to control the sounding of the notes in certain forms of key-controlled musical instruments, comprising the well known manual key and a simple form of key-operable valve, with which the pneumatic coupler of Fig. 1 is also designed to co-operate.

Before proceeding with the detailed description of the construction, it may be well to explain that, while the pneumatic coupler herein shown is in the form of what is known as an octave coupler for use in a combined key and automatically controlled organ or piano, and will be described as such, the construction is equally well adapted for other uses, some of which will be pointed out following the detailed description, and it is to be understood that the invention is not limited, therefore, to the exact form or connection of the parts shown in the drawings.

Octave couplers are employed for effecting, at will, the coupling of the note-sounding devices of musical instruments in octaves, so that, simultaneously with the sounding of any note in the instrument scale, another note of the same denomination in a different part of the scale will be sounded. As is well known in this art, any one note may be coupled in this manner with one or more notes of the same denomination one or more octaves above or below the principal note, such note-coupling devices being known as octave, super-octave, and sub-octave couplers.

The pneumatic coupler herein shown is a single octave coupler, provided with one series of connections extending to the valves of a key-operable valve-action, and with another series of connections extending to the valves of a tracker-controllable valve-action, the obvious purpose of such double connections being to provide for the use of the coupler when the instrument is played either manually or automatically, as well as both manually and automatically.

In Figure 1, the pneumatic coupler C is shown as comprising a horizontally extending duct-bar 1, from the lower part of which a series of tubular conduits 2, 3 and 4 extend for connection with individual ducts in a key-operable valve-action K (Fig. 4), and from the upper part of which a separate series of tubular conduits 5 and 6 extend for connection with individual ducts in a tracker-controllable valve-action T (Fig. 3). In order to avoid confusion through duplication of the parts, but one valve has been shown in each of the valve-actions K and T, but it

will be understood that, in actual use, there is one of each of these valves for each note in the musical instrument scale. For the purposes of this description, it will be assumed that the left-hand section through the duct-bar 1 cuts the ducts pertaining to what will be termed a principal note "C", while the right-hand section cuts the ducts pertaining to the note "C", one octave above.

- 5 10 Each key-valve 7 (Fig. 4), excepting those pertaining to the notes of the upper octave of the scale (not illustrated), controls a pair of ports 8 and 9, which open out upon the under surface of the key-valve-bar 10. The 15 ducts 11 and 12 for ports 8 and 9, respectively, are connected by the individual tubular conduits 2 and 3 with duct 13 (Fig. 1) of the principal note "C" and with duct 14 of the octave note "C". Conduit 4 extends to a 20 key-valve (not illustrated) similar to, but located one octave above, key-valve 7 and is connected with a corresponding duct 13, serving the octave note "C" the same as conduit 2 serves the principal note "C". Conduits 2 25 and 4 are provided with branch-conduits 15 and 16, respectively, which extend to note-valves (not illustrated, since they may be of any well known or preferred construction and are not an essential part of this invention) 30 individually controlling the sounding of the respective notes "C" and "C". The operation of these note-valves and the sounding of their respective notes is effected by the admission of atmospheric air through conduits 35 2 and 4, either by the opening of the corresponding key-valves 7 or by the opening of valves to be hereinafter described, the last-named valves being located in and upon the pneumatic coupler C.
- 40 Each tracker-valve 17 (Fig. 3) controls the collapse and expansion of a corresponding one of a series of pneumatics 18 (Fig. 1) in the following well known manner. The tracker-controllable valve-action T comprises a chamber 19 from which air is exhausted in the usual or any preferred manner, not necessary to describe. The upper wall 20 of chamber 19 is provided with a series of separate valve-chambers 21, one for each note, 45 which are individually connected by ducts 22 and tubular conduits, such as 5 and 6, each with a corresponding duct 23 and pneumatic 18, and are provided with oppositely disposed ports 24 and 25, the ports 24 opening to the atmosphere and the ports 25 opening into chamber 19. Conduit 5 extends between ducts 22 and 23 and serves to connect the pneumatic 18 and valve 17 pertaining to the principal note "C", while conduit 6 extends between 50 and connects similar ducts and the pneumatic and valve pertaining to the octave note "C". Each valve 17 is carried upon a valve-stem 26 and is operated by a diaphragm-pneumatic or "puff" 27 to control the connection of the 55 corresponding valve-chamber 21 and duct 22

alternately with their respective ports 24 and 25, the operation of each puff 27 being controlled by the admission and exclusion of atmospheric air to and from the pocket or recess 28 beneath said puff, through the respective tracker-tube 29 and tracker-duct 30 of the tracker 31, through the co-operation of the usual perforated music sheet 32, all in the manner well known in this art.

70 Each pneumatic 18 (Fig. 1) is hinged at 33 and is provided with an arm 34, which extends over the hinge and carries a valve 35. A spring 36 acts against each arm 34 to hold the pneumatic 18 normally expanded and the valve 35 closed. Each valve 35, excepting 75 those pertaining to the notes of the upper octave of the scale (not illustrated), controls a pair of ports 37 and 38, which open out upon the surface of duct-bar 1. Port 37 is the atmospheric terminus of a duct 39, to be presently described, and port 38 is the atmospheric terminus of a short duct 40 which connects with duct 13.

80 It will now be seen that the sounding of each principal note may be controlled manually by the manipulation of the respective manual key, the depression of each key effecting the opening of the respective key-valve 7 and the admission of atmospheric air to the corresponding note-valve through the respective port 8, duct 11, conduit 2, and branch-conduit 15. Similarly, the sounding of each principal note may be controlled automatically from the music sheet 32. As the perforations in the music sheet selectively register with the corresponding apertures in tracker 31, atmospheric air will be admitted to the respective tracker-ducts 30, tracker-tubes 29, and recesses 28, and the reduced air-pressure within chamber 19 will instantly effect the raising of the corresponding puffs 27 and valves 17. The raising of each valve 17 closes the respective port 24 and opens the oppositely disposed port 25, shutting off the communication of the corresponding pneumatic 18 with the atmosphere and connecting it with chamber 19, through duct 23, conduit 5, duct 22, and valve-chamber 21, thus effecting the collapse of said pneumatic and the opening of the valve 35 carried thereby. The opening of each valve 35 admits atmospheric air to ports 37 and 38 controlled thereby, and to the respectively connected ducts 39 and 40. Duct 40 being connected with duct 13, the atmospheric air admitted thereto will pass to conduit 2 and branch-conduit 15, and effect the operation of the respective note-valve in the same manner as that accomplished by the opening of the respective key-valve 7 and port 8.

85 90 95 100 105 110 115 120 125 130 135 140 As shown in Figure 1, a member 41 extends horizontally along the rear surface of duct-bar 1 and is provided with an air-tight chamber 42, one wall of which chamber is formed by a single flexible diaphragm 43. A tubular

conduit 44 connects the interior of chamber 42 with a duct 45 (Figs. 1 and 2) controlled by the manually operable coupler draw-stop 46. Reciprocal movement of draw-stop 46 effects a similar movement of the connected sliding D-valve 47 within a pressure-chamber 48, to which air-pressure is supplied in the usual or any preferred manner, not necessary to describe. This reciprocal movement of D-valve 47 alternately connects duct 45, conduit 44, and chamber 42 with the atmosphere and with the pressure-chamber. When the D-valve 47 is in the full-line position shown in Fig. 2, it will cover duct 45 and connect it with the atmosphere through duct 49^a, chamber 42 will not be served with air-pressure, diaphragm 43 will be relaxed, and the pneumatic coupler will be in operative condition. When the D-valve 47 is in the dotted-line position shown in Fig. 2, it will uncover duct 45, disconnecting it from duct 49^a and exposing it to the air-pressure in pressure-chamber 48, chamber 42 will be supplied with air-pressure, diaphragm 43 will be distended, and the pneumatic coupler will be thus rendered inoperative, in a manner to be described.

Each duct 13, excepting those pertaining to the notes of the lowest octave of the instrument scale, extends to the rear surface of duct-bar 1 and terminates thereupon in a port 49. Around each of these ports 49, a circular groove 50 is formed (see Fig. 1^a), leaving a boss 51 which forms a seat for a circular diaphragm or "puff" 52, each puff being secured about its edge-part to the surface of duct-bar 1 beyond the outer edge of the circular groove 50. Preferably, the outer surface of each puff 52 is provided with a centrally located disc 53, secured upon the puff to insure its proper seating upon the boss 51 to act as a valve for port 49 and for two other ports, 54 and 55, which open out upon the boss 51 above and below port 49, respectively. These ports 54 and 55 are complementary to port 49, their communication therewith being controlled by the same puff 52 and disc 53. Port 54 opens into a duct 56 and port 55 opens into the duct 14, and both of said ducts are controlled by valves pertaining to the note one octave below. Referring, at this point, to the right-hand section in Figure 1, it will be seen that duct 56 for the note "C" is connected by a tubular conduit 57 with duct 39 for the note "C" and is controlled by the valve 35 carried by the pneumatic 18 pertaining to that note, and it will also be seen that duct 14 for the note "C" is connected by tubular conduit 3 with duct 12 (Fig. 4) for the note "C" and is controlled by the key-valve 7 pertaining to that note. It is to be understood that ducts 56 and 14 for the note "C" are similarly connected, by their respective conduits 57 and 3, to be controlled by valves

35 and 7 pertaining to the note "CC" (not illustrated), one octave below.

A novel and important feature of this invention resides in the fact that, with the construction herein shown, there can be no leakage of air or communication between the different puffs 52, or between such puffs and the chamber 42. Diaphragm 43 seals the chamber 42, and is secured to and removable with the member 41. The puffs 52 are individually sealed about their edges upon the duct-bar 1 to segregate each group of ports 49, 54 and 55 pertaining to each note of the instrument scale, and the space between said diaphragm 43 and said puffs 52 is open, at the ends of the member 41, to the atmosphere. Consequently, if there should be any leakage of air through or at the edges of either the diaphragm 43 or any one or more of the several puffs 52, there will be no communication of such air-leakage to the ports and ducts pertaining to other notes. Furthermore, with this construction, a leaky puff 52 will not interfere with the positive action of the diaphragm 43 in closing the respective port 49, when the coupler is to be held inoperative.

The operation of the pneumatic coupler will now be described. As already mentioned, when the coupler draw-stop 46 is in its "off" position, with D-valve 47 in the dotted-line position shown in Fig. 2, chamber 42 will be supplied with air-pressure from pressure-chamber 48, through duct 45 and conduit 44, and diaphragm 43 will be distended, or blown outwardly to the right (as viewed in Fig. 1), to bear against all of the discs 53 and hold the central portion of all of the puffs 52 pressed against their respective bosses or seats 51 to close the entire series of individually grouped ports 49, 54 and 55. Under such circumstances, the pneumatic coupler will be held in inoperative condition, and the admission of atmospheric air to branch-conduits 15 and 16, and the consequent sounding of the notes controlled by the note-valves connected with said branch-conduits, may be controlled by the operation of valves 35, under control from tracker 31, or by the operation of key-valves 7, operated by manipulation of the respective manual keys, as hereinbefore described.

When the draw-stop 46 is drawn to its "on" position, with D-valve 47 in the full line position shown in Fig. 2, chamber 42 will be disconnected from pressure-chamber 48 and connected with the atmosphere, and diaphragm 43 will be released from holding puffs 52 pressed against seats 51. In this manner, the pneumatic coupler will be placed in operative condition. Now, as the different manual keys are depressed and the respective key-valves 7 are opened thereby to uncover ports 8 and 9 and admit atmospheric air to ducts 11 and 12, the respective principal note for

each key will be sounded in the manner already described, through the several note-valves served by branch-conduits 15 and 16, and, in addition, the respective octave note for each key will be sounded in the following manner. The atmospheric air admitted through each opened port 9 will pass, through duct 12 and conduit 3, to duct 14 of the octave note, to port 55 pertaining to said octave note, under the released puff 52, to port 49 and duct 13, and through conduit 4 and branch-conduit 16, to the note-valve for said octave note.

In a similar manner, when the respective valves 35 are opened, under the control of the music sheet 32 as hereinbefore described, to uncover ports 37 and 38 and admit atmospheric air to ducts 39 and 40, the respective principal note for each valve 35 will be sounded in the manner already described, through the several note-valves served by branch-conduits 15 and 16, and, in addition, the respective octave note for each valve 35 will be sounded in the following manner. The atmospheric air admitted through each opened port 37 will pass, through duct 39 and conduit 57, to duct 56 of the octave note, to the port 54 pertaining to said octave note, under the released puff 52, to port 49 and duct 13, and through conduit 4 and branch-conduit 16, to the note-valve for said octave note.

It has been mentioned that the pneumatic coupler herein shown is not limited to use as an octave coupler. The two sections shown in Figure 1 have been described as taken through different parts of the same coupler unit, cutting the ducts therein pertaining to notes one octave apart, but it is only necessary to consider these sections as being taken through separate coupler units which may pertain to different divisions of the same instrument or to different instruments, and it will be realized that the construction and the invention embodied therein are adaptable, without change, to different uses. Consequently, excepting where specifically stated, the appended claims are not to be construed as referring to octave couplers only.

60 I claim—

1. The combination, with a musical instrument having a plurality of note-sounding devices and valves (7) individual to said devices selectively operable to control the operation thereof, of a pneumatic coupler having a first series of ducts (13) individually connected with and serving said devices, a second series of ducts (14) individually connected with and served by said valves, coupler-valves (52) controlling the individual connection of the respective ducts of said first and said second series, and a single pneumatically operable element (43) operating to bear upon and control the operation of a plurality of said coupler-valves.

2. The combination, with a musical instrument having a plurality of note-sounding devices and valves individual to said devices selectively operable to control the operation thereof, of a pneumatic coupler having a first series of ducts individually connected with and serving said devices, a second series of ducts individually connected with and served by said valves, coupler-valves controlling the individual connection of the respective ducts of said first and said second series, and a single diaphragm operating to bear upon and control the operation of a plurality of said coupler-valves. 70

3. The combination, with a musical instrument having a plurality of note-sounding devices and valves individual to said devices selectively operable to control the operation thereof, of a pneumatic coupler having a first series of ducts individually connected with and serving said devices, a second series of ducts individually connected with and served by said valves, coupler-valves controlling the individual connection of the respective ducts of said first and said second series, an air-chamber, a single diaphragm forming a flexible wall of said air-chamber and operating upon the alternate application and release of air-pressure to and from said air-chamber to bear upon and control the operation of a plurality of said coupler-valves, and means operating to control the application and release of air-pressure to and from said air-chamber. 75

4. The combination, with a musical instrument having a plurality of note-sounding devices and a first (7) and a second (35) series of valves, the valves of each of said series being individual to said devices and selectively operable to control the operation thereof, of a pneumatic coupler having a first series of ducts (13) individually connected with and serving said devices, a second series of ducts (14) individually connected with and served by the valves of said first series of valves, a third series of ducts (56) individually connected with and served by the valves of said second series of valves, coupler-valves (52) controlling the individual connection of the ducts of said first series of ducts with the respective ducts of said second and third series of ducts, and a single pneumatically operable element (43) operating to control the operation of a plurality of said coupler-valves. 80

5. The combination, with a musical instrument having a plurality of note-sounding devices and a first and a second series of valves, the valves of each of said series being individual to said devices and selectively operable to control the operation thereof, of a pneumatic coupler having a first series of ducts individually connected with and serving said devices, a second series of ducts individually connected with and served by the valves of

100

105

- said first series of valves, a third series of ducts individually connected with and served by the valves of said second series of valves, coupler-valves controlling the individual connection of the ducts of said first series of ducts with the respective ducts of said second and third series of ducts, and a single diaphragm operating to control the operation of a plurality of said coupler-valves.
6. The combination, with a musical instrument having a plurality of note-sounding devices and a first and a second series of valves, the valves of each of said series being individual to said devices and selectively operable to control the operation thereof, of a pneumatic coupler having a first series of ducts individually connected with and serving said devices, a second series of ducts individually connected with and served by the valves of said first series of valves, a third series of ducts individually connected with and served by the valves of said second series of valves, coupler-valves controlling the individual connection of the ducts of said first series of ducts with the respective ducts of said second and third series of ducts, an air-chamber, a single diaphragm forming a flexible wall of said air-chamber and operating upon the alternate application and release of air-pressure to and from said air-chamber to control the operation of a plurality of said coupler-valves, and means operating to control the application and release of air-pressure to and from said air-chamber.
7. The combination, with a musical instrument having a plurality of note-sounding devices, valves (7) individual to said devices and selectively operable to control the operation thereof, and a first (8) and a second (9) series of ports, one port of each of said series being controlled by one of said valves, of a pneumatic coupler having a first series of ducts (13), each duct thereof being connected with one port of said first series of ports controlled by one of said valves, a second series of ducts (14), each duct thereof being connected with one port of said second series of ports controlled by another of said valves, coupler-valves (52) controlling the individual connection of the ducts of said first series of ducts with the respective ducts of said second series of ducts, and a single pneumatically operable element (43) operating to control the operation of a plurality of said coupler-valves.
8. The combination, with a musical instrument having a plurality of note-sounding devices, valves individual to said devices and selectively operable to control the operation thereof, and a first and a second series of ports, one port of each of said series being controlled by one of said valves, of a pneumatic coupler having a first series of ducts, each duct thereof being connected with one of said devices and with one port of said first
- series of ports controlled by one of said valves, a second series of ducts, each duct thereof being connected with one port of said second series of ports controlled by another of said valves, coupler-valves controlling the individual connection of the ducts of said first series of ducts with the respective ducts of said second series of ducts, and a single pneumatically operable element operating to control the operation of a plurality of said coupler-valves.
9. The combination, with a musical instrument having a plurality of note-sounding devices, a first (7) and a second (35) series of valves, the valves of each of said series being individual to said devices and selectively operable to control the operation thereof, and a pair of ports controlled by each valve of said first and second series of valves, of a pneumatic coupler having a first series of ducts (13), each duct thereof being connected with one of said devices, with one of said pair of ports controlled by one of the valves of said first series of valves, and with one of said pair of ports controlled by one of the valves of said second series of valves; a second series of ducts (14), each duct thereof being connected with the other one of said pair of ports controlled by one of the valves of said first series of valves; a third series of ducts (56), each duct thereof being connected with the other one of said pair of ports controlled by one of the valves of said second series of valves; coupler-valves controlling the individual connection of the ducts of said first series of ducts with the respective ducts of said second and third series of ducts; and a single pneumatically operable element operating to control the operation of a plurality of said coupler-valves.
10. The combination, with a key-controlled musical instrument having a plurality of note-sounding devices, a plurality of keys, and a series of key-valves individual to said devices and selectively operable by said keys to control the operation of said devices, of a pneumatic coupler having a first series of ducts individually connected with and serving said devices, a second series of ducts individually connected with and controlled by said key-valves, coupler-valves controlling the individual connection of the respective ducts of said first and second series of ducts, and a single pneumatically operable element operating to bear upon and control the operation of a plurality of said coupler-valves.
11. The combination, with an automatic musical instrument having a plurality of note-sounding devices, a tracker, and a series of tracker-valves individual to said devices and selectively operable under the control of said tracker to control the operation of said devices, of a pneumatic coupler having a first series of ducts individually connected with and serving said devices, a second series of

ducts individually connected with and controlled by said tracker-valves, coupler-valves controlling the individual connection of the respective ducts of said first and second series of ducts, and a single pneumatically operable element operating to bear upon and control the operation of a plurality of said coupler-valves.

12. The combination, with a combined key and automatically controlled musical instrument having a plurality of note-sounding devices, a plurality of keys, a tracker, a series of key-valves individual to said devices and selectively operable by said keys to control the operation of said devices, and a series of tracker-valves individual to said devices and selectively operable under the control of said tracker to control the operation of said devices, of a pneumatic coupler having a first series of ducts individually connected with and serving said devices; a second series of ducts individually connected with and controlled by said key-valves, a third series of ducts individually connected with and controlled by said tracker-valves, coupler-valves controlling the individual connection of the ducts of said first series of ducts with the respective ducts of said second and third series of ducts, and a single pneumatically operable element operating to control the operation of a plurality of said coupler-valves.

13. The combination, with a combined key and automatically controlled musical instrument having a plurality of note-sounding devices, a plurality of keys, a tracker, a series of key-valves individual to said devices and selectively operable by said keys to control the operation of said devices, and a series of tracker-valves individual to said devices and selectively operable under the control of said tracker to control the operation of said devices, of a pneumatic coupler having a series of principal note ducts individually connected with and serving said devices, a first series of octave note ducts individually connected with and served by said key-valves, a second series of octave note ducts individually connected with and served by said tracker-valves, coupler-valves controlling the individual connection of each of said principal note ducts with an octave note duct of each said first and second series of octave note ducts, and a single pneumatically operable element operating to control the operation of a plurality of said coupler-valves.

14. The combination, with a musical instrument having a plurality of note-sounding devices, a series of valves (7) individual to said devices and manually controllable in operation to selectively control the operation of said devices, and a series of valves (35) individual to said devices and automatically controllable in operation to selectively control the operation of said devices, of a pneumatic coupler having a series of principal

note ducts (13) individually connected with and serving said devices, a first series of octave note ducts (14) individually connected with and served by said manually controllable valves, a second series of octave note ducts (56) individually connected with and served by said automatically controllable valves, coupler-valves operating to control the individual connection of each of said principal note ducts with a respective duct of each of said series of octave note ducts, and a single pneumatically operable element operating to control the operation of a plurality of said coupler-valves.

15. The combination, with a musical instrument having a plurality of note-sounding devices, valves individual to said devices and selectively operable to control the operation thereof, a first and a second series of ports, one port of each of said series being controlled by one of said valves, and connections individually connecting the ports of said first series with said note-sounding devices, of a pneumatic coupler having a series of principal note ducts, each duct thereof being connected with one of said note-sounding devices; a series of octave note ducts, each duct thereof being connected with one of said second series of ports; coupler-valves controlling the individual connection of each octave note duct with its respective principal note duct; and a single pneumatically operable element operating to bear upon and control the operation of a plurality of said coupler-valves.

16. The combination, with a musical instrument having a plurality of note-sounding devices; a first and a second series of valves, the valves of each of said series being individual to said devices and selectively operable to control the operation thereof; and a pair of ports controlled by each of said valves, the first port of each pair being connected with one of said note-sounding devices; of a pneumatic coupler having a series of principal note ducts, each duct thereof being connected with one of said note-sounding devices; a first series of octave note ducts connected with the second port of each pair of ports controlled by each valve of said first series of valves; a second series of octave note ducts connected with the second port of each pair of ports controlled by each valve of said second series of valves; coupler-valves controlling the individual connection of each duct of said series of principal note ducts with a respective duct of said first and said second series of octave note ducts; and a single pneumatically operable element operating to control the operation of a plurality of said coupler-valves.

17. A pneumatic coupler for musical instruments comprising a duct-bar having a series of ducts and individual ports therefor, said ports opening out upon one face of said duct-bar; a series of flexible diaphragms se-

- cured upon said one face of said duct-bar, each diaphragm covering one of said ports and separating it from other ports; an air-chamber extending over said port-covering diaphragms; a flexible controlling diaphragm forming one wall of said air-chamber and spaced slightly from said port-covering diaphragms, the space between said controlling diaphragm and said port-covering diaphragms being in free communication with the atmosphere, said controlling diaphragm operating, when distended by the application of air-pressure to said air-chamber, to hold a plurality of said port-covering diaphragms pressed against said duct-bar to close their respective ports, and means operating to alternately apply and release air-pressure to and from said air-chamber.
18. A pneumatic coupler for musical instruments comprising a duct-bar having a series of ducts and individual ports therefor, said ports opening out upon one face of said duct-bar; a series of flexible diaphragms secured upon said one face of said duct-bar, each diaphragm covering one of said ports and separating it from other ports; a valve-disk secured upon each of said diaphragms; an air-chamber extending over said port-covering diaphragms; a flexible controlling diaphragm forming one wall of said air-chamber and spaced slightly from said port-covering diaphragms, the space between said controlling diaphragm and said port-covering diaphragms being in free communication with the atmosphere, said controlling diaphragm operating, when distended by the application of air-pressure to said air-chamber, to hold a plurality of said disks and their respective port-covering diaphragms pressed to close their respective groups of ports and prevent intercommunication thereof; and means controllable at will and operating to alternately apply and release air-pressure to and from said air-chamber.
19. A pneumatic coupler for musical instruments comprising a duct-bar having a plurality of series of ducts and a plurality of series of ports individual thereto, said ports opening out upon one face of said duct-bar and being arranged thereupon in groups, there being one port of each of said series in each group; a series of flexible diaphragms secured upon said one face of said duct-bar, each diaphragm covering one group of said ports and separating that group from other groups; an air-chamber extending over said port-covering diaphragms; a flexible controlling diaphragm forming one wall of said air-chamber and spaced slightly from said port-covering diaphragms, the space between said controlling diaphragm and said port-covering diaphragms being in free communication with the atmosphere, said controlling diaphragm operating, when distended by the application of air-pressure to said air-chamber, to hold a plurality of said port-covering diaphragms pressed against said duct-bar to close their respective groups of ports and prevent intercommunication thereof, and means operating to alternately apply and release air-pressure to and from said air-chamber.
20. A pneumatic coupler for musical instruments comprising a duct-bar having a plurality of series of ducts and a plurality of series of ports individual thereto, said ports opening out upon one face of said duct-bar and being arranged thereupon in groups, there being one port of each of said series in each group; a series of flexible diaphragms secured upon said one face of said duct-bar, each diaphragm covering one group of said ports and separating that group from other groups; a valve-disk secured upon each of said diaphragms; an air-chamber extending over said port-covering diaphragms; a flexible controlling diaphragm forming one wall of said air-chamber and spaced slightly from said port-covering diaphragms, the space between said controlling diaphragm and said port-covering diaphragms being in free communication with the atmosphere, said controlling diaphragm operating, when distended by the application of air-pressure to said air-chamber, to hold a plurality of said disks and their respective port-covering diaphragms pressed to close their respective groups of ports and prevent intercommunication thereof; and means controllable at will and operating to alternately apply and release air-pressure to and from said air-chamber.
21. A pneumatic coupler for musical instruments comprising a duct-bar having a plurality of series of ducts, a series of coupler-valves controlling the inter-communication of corresponding ducts of each series, an air-chamber fixed with relation to said duct-bar, and a controlling diaphragm forming a flexible wall of said air-chamber and acting, upon the alternate application and release of air-pressure to and from said air-chamber, to control the operation of a plurality of said coupler-valves and thereby control the inter-communication of corresponding ducts of said plurality of series of ducts.
22. A pneumatic coupler for musical instruments comprising a duct-bar having a series of principal note ducts (13) and a series of valve-controlled atmospheric ports (40) opening into the respective ducts of said series; a series of octave note ducts (56) and a series of valve-controlled atmospheric ports (37) connected with the respective ducts of said series; a series of valves (35), each valve thereof controlling one atmospheric port of each of said series of ducts; a series of coupler-valves (52), each valve thereof controlling the communication of one of said principal note ducts with one of said octave note ducts.

ducts; and a single pneumatically operable element operating to control the operation of a plurality of said coupler-valves.

23. A pneumatic coupler for musical instruments comprising a duct-bar having a series of principal note ducts and a series of valve-controlled atmospheric ports opening into the respective ducts of said series; a series of octave note ducts and a series of valve-controlled atmospheric ports connected with the respective ducts of said series; a series of pneumatics secured upon said duct-bar and a series of valves actuated by said pneumatics, each pneumatic and the valve actuated thereby controlling one atmospheric port of each of said series of ducts; a series of coupler-valves, each valve thereof controlling the communication of one of said principal note ducts with one of said octave note ducts; a duct extending from each of said pneumatics, through which the operation of the respective pneumatics may be controlled; an air-chamber having a flexible wall operating upon the alternate application and release of air-pressure to and from said air-chamber to control the operation of a plurality of said coupler-valves; and a conduit extending from said air-chamber through which the application and release of air-pressure to and from said air-chamber may be controlled.

In witness whereof, I have hereunto subscribed my name this 17th day of January, A.D. 1927.

LEWIS T. BARKSTROM.

Attest:

John W. Borchard, Secretary
and Principal Attorney of the Law Firm of
Borchard, Borchard & Borchard, of St. Paul,
Minnesota, for the Inventor.
